FRANK H. BALL, OF DETROIT, MICHIGAN, ASSIGNOR TO BALL & BALL CARBURETOR COMPANY, OF DETROIT, MICHIGAN, A CORPORATION OF MICHIGAN.

CARBURETER.

1,391,930.

Specification of Letters Patent. Patented Sept. 27, 1921.

Application filed June 10, 1919. Serial No. 303,206.

To all whom it may concern:

Be it known that I, FRANK H. BALL, a citizen of the United States, residing at Detroit, in the county of Wayne and State of Michigan, have invented new and useful Improvements in Carbureters, of which the following is a specification.

In the operation of a carbureter it is desirable to completely atomize the fuel. With a wide open throttle and a rapid speed of the engine there is a sufficient velocity of the air through the contracted portion of the suction passage, usually in the form of a Venturi tube to accomplish this purpose. When there is a partially closed throttle and sufficient speed of the engine there is a sufficient velocity of air past the throttle to accomplish the purpose. In one instance the restriction is at the Venturi tube and in the other instance the restriction is made by the throttle. Where, however, there is a comparatively wide open throttle and a slow movement of the motor as is apt to be the condition on a hill with an automobile there is not sufficient velocity of air through the carbureter to properly atomize the fuel. In addition to this the mixture is not usually sufficiently rich to give the maximum power so that under these conditions there is a lack of sufficiently rich mixture to give the maximum power even though the atomization were complete which condition is aggravated by a lack of atomization so that the ultimate result is for all practical purposes a leaner mixture is provided than the mixture delivered under other conditions. It is desirable, therefore, to supplement the normal fuel supply where there is a slow movement of air through the suction passage so as to give the most efficient mixture under these conditions and to continue this supplemental supply so long as the slow movement of air continues. The mechanism for accomplishing this I term a "step up device." If this can be attained automatically a very lean mixture may be provided for other working conditions so that there will be an economy of fuel as well as a satisfactory performance under the varying conditions above mentioned.

With a quick opening of the throttle there is a momentary disturbance in condition which results in a leaner mixture than is desirable and this has been corrected by

what has been commonly called pick-up devices. With such devices an added amount of fuel is momentarily supplied as the throttle is opened to bridge over the disturbing condition while the engine is picking up due to the opening of the throttle. Such a momentary addition of fuel is desirable even with a step-up device for a continued supplementing of the fuel under the conditions above described. With the present invention this is accomplished.

The invention is illustrated in the accompanying drawings wherein a carbureter is shown in vertical section.

1 marks the suction passage, 2 the throttle, 3 the Venturi tube, 4 fuel nozzles which as shown project from the walls of the Venturi tube, 5 an annular chamber around the Venturi tube and from which the fuel nozzles lead, 6 a passage connecting the annular chamber 5 with an intermediate chamber 7 formed between the walls of a socket 8 formed in the body of the carbureter and the walls of a metering plug 9. The metering plug has a metered fuel opening 10 which leads to a passage 11 in the plug and the passage 11 communicates with the chamber 7 by means of a radial passage 12. A fuel passage 13 leads from a float chamber 14 to the metered opening 10. The float chamber has the usual supply connection 15 controlled by a valve 16 and the valve is controlled by a float 17 in the usual manner.

The fuel is regulated by the reduction of pressure or suction at the metered opening 10. The reduced pressure at the Venturi tube is communicated to the passage 11 by way of the nozzles 4, passage 6, chamber 7 and passage 12. The suction may be modified by admitting a certain amount of air preferably from the atmosphere and further it is possible by this method to avoid the negative head necessary where the fuel is delivered in the form of raw fuel to the nozzle. Air is admitted through the passage 19 to a passage 18 in the plug 9. A restricted opening 20 communicates with the passages 18 and 11. A passage 21 also leads from the passage 18 to the chamber 7. With the passages admitting air to the chambers between the fuel restriction 10 and the nozzles 4 the suction at the metered opening 10 follows the suction of the suction passages but this suction is reduced by the introduc-

tion of the air. The fuel level is indicated at A—A. The fuel level is approximately at the passage 12 and by reason of the fact that the nozzles 4 extend above the fuel level 5 the leakage of fuel when the carburetor is at rest is obviated. On the other hand the air breaking up the fuel at the level of the chamber 6 maintains the level to which the fuel is delivered approximately at or below 10 the fuel level and the fuel is atomized more or less as it is delivered through the nozzles.

The step up device for varying the quality of the mixture under the conditions heretofore set forth are as follows:—The chamber 15 7 is connected with a passage or chamber 22 by a passage 23. The chamber 22 opens to the atmosphere and is controlled by a valve 24. The valve 24 has a stem 25 which terminates in a piston 26. The piston operates in a cylinder 27. The cylinder is connected by a passage 28 with the suction passage at a point above the throttle. A spring 29 is arranged on the stem 25 and operates against 20 a shoulder 30 on the stem 25 and rests against a shoulder 31 at the end of the cylinder 27. The spring is of sufficient strength to retain 25 the valve 24 in closed position until there is such a preponderance of pressure below the piston 26 as to overcome the spring and open the valve.

When there is a wide open throttle and a slow running motor there is of course, very little reduction of pressure in the suction 30 passage and consequently a very small reduction of pressure in the cylinder 27. Consequently the preponderance of atmospheric 35 pressure over suction passage pressure is not sufficient to overcome the spring 29 so as to open the valve 24. The valve 24 remains in a closed position and the reduction in pressure in the passage 11 inducing a flow 40 through the metered opening 10 is a pressure between that of the Venturi tube and the atmosphere depending on the size of the 45 openings admitting air into the passage 11 and the size of the nozzles forming a means of communication between the passage 11 and the Venturi tube. These are so proportioned as to give a comparatively rich 50 mixture so that the mixture is better adapted to the higher power desired under such conditions but more particularly it supplements the fuel so as to make up for the lack 55 of atomization. When, however, the motor speeds up or a speed is maintained with a partially closed throttle so that there is a higher velocity at the restrictions of the suction passage there is a corresponding 60 reduction of pressure at the discharge side of the throttle which is communicated through the passage 28 to the cylinder 27 and a consequent reduction of pressure above the piston 26 creates a preponderance of pressure 65 below the piston which overcomes the

spring 29 and lifts the valve 24, the amount of the opening being dependent on the degree of reduction of pressure.

As the valve 24 is opened air is admitted to the passage or chamber 7 and communicated to the passage 11 so that the reduction of pressure in the passage 11 is less and in consequence the suction effort on the fuel at the restricted opening 10 is reduced, with a consequent reduction in the quantity of fuel 75 delivered. In addition there is a slightly greater amount of air delivered through the nozzles 4 which also tends to make a leaner mixture.

The device so far as described gives a 80 continuing supplemental supply of fuel during certain conditions. As before stated it is desirable to momentarily supply additional amounts of fuel by way is commonly called a pick-up device. This is accomplished in the 85 present invention as follows:—

A well 32 is arranged below the chamber 22 and separated therefrom by a partition plate or plug 33. A depending tube 34 extends from the plug 33 to near the bottom 90 of the well 32 and is provided with a restricted opening 35 at its lower end. The well 32 is connected with the fuel passage 13 by a small passage 36. A passage 37 extends from the well 32 to a passage 38 which is open at its top to the atmosphere. Fuel accumulates in the well 32 and in the passage 38 to the level shown in the drawings. The fuel remains at this level so long as the valve 24 is opened, the opening of the valve 100 allowing the movement of air to the chamber 32 so nearly approximating atmospheric pressure as to preclude the transfer of fuel from the well 32 to the chamber 22. When, however, the valve 24 is closed the pressure 105 in the chamber 22 is reduced to the pressure of the chamber 7 and this reduction of pressure results in a preponderance of pressure on the column of fuel in the passage 38. Fuel is, therefore, forced from the passage 38, well 32, through the opening 35 through the chamber 22, passage 23 to the chamber 7. The delivery of the accumulated liquid from the well momentarily adds very materially to the fuel supplied and affords 110 what is commonly known as a pick-up delivery of fuel. As soon as the accumulated fuel in the passage 38 and well 32 is exhausted the delivery is very largely cut off. There is a slight amount of liquid picked 115 up by the air moving through the well 32 and passage 35 and carried into the suction passage with the other fuel supply and this is considered in the added fuel supply which is delivered through the metered opening 10 120 as an incident to the increased suction on the fuel due to the closing of the valve 24. The admission of air, however, through the channel starting with the passage 38 reduces 125 slightly the suction effort that would other- 130

wise be present on the metered opening 10 so that while there is a small added amount of fuel carried through the opening 35 there is also a smaller amount of fuel carried 5 through the metered opening 10 than would be carried through said opening 10 if there were a complete closure as to the passage of air through the passage 23.

It will be seen, therefore, that in the 10 present construction not only the pick-up device but the step up device for continuing a supplemental supply of fuel is responsive to and actuated by variations of pressure in the suction passage and that in both 15 devices the fuel is actuated by the direct action of the air upon the fuel.

In the drawings the parts are shown 20 at rest. In operation a closing of the throttle opens the valve 24. It will be understood 25 that as the valve 24 is closed the accumulated fuel in the well is discharged and the level of fuel in the chamber 6 is brought to the floor of this chamber.

What I claim as new is:—

25 1. In a carbureter, the combination of a suction passage; means for delivering a combustible mixture comprising as its elements air and fuel to said passage, the fuel being passed through a conduit delivering 30 at least the major portion of the fuel supply for the combustible mixture; pick-up and step up devices, said devices modifying said delivery through said conduit by the direct action of inflowing air to vary 35 the relative flow of said elements to the suction passage to form a richer mixture with a lesser degree of vacuum and to momentarily further increase the richness of the mixture immediately following such variation; 40 and mechanism responsive to variations of pressure in the suction passage actuating said devices.

2. In a carbureter, the combination of a 45 suction passage; a throttle valve; means for delivering a combustible mixture comprising as its elements air and fuel to said passage; pick-up and continuous fuel augmenting devices, said devices modifying said delivery through said conduit by the direct 50 action of inflowing air to vary the relative flow of said elements to the suction passage to form a richer mixture with a lesser degree of vacuum and to momentarily further increase the richness of the mixture immediately following such variation; and mechanism responsive to variations of pressure 55 in the suction passage at the discharge side of the throttle actuating said devices.

3. In a carbureter, the combination of a 60 suction passage; means for delivering a combustible mixture comprising as its elements air and fuel to said passage, the fuel being passed through a conduit delivering at least the major portion of the fuel supply for the 65 combustible mixture; and devices actuated

by variations in the degree of vacuum in the suction passage and continuing during such variation modifying said delivery through said conduit to vary the relative flow of said elements to said suction passage 70 to form a richer mixture with a lesser degree of vacuum and to momentarily further increase the richness of the mixture immediately following such variation.

4. In a carbureter, the combination of a 75 suction passage; means for delivering air and fuel to the suction passage comprising a chamber communicating with the suction passage, with a fuel supply and air passages leading to an air supply; and valve 80 mechanism responsive to variations of pressure in the suction passage and acting on said air passages to vary the air flow therethrough to control the relative flow of air and fuel to the suction passage to momentarily supplement the fuel supply by the 85 direct action of air on the fuel immediately following a variation of pressure in the suction passage and for continuously adding to the fuel flow to enrich the mixture 90 during a continuation of the change of pressure in the suction passage.

5. In a carbureter, the combination of a 95 suction passage; an intermediate chamber communicating with the suction passage, a source of fuel supply and with the atmosphere; a well in which fuel accumulates 100 communicating with the atmosphere; a passage leading from the lower part of the well to said chamber; a valve varying the communication between the chamber and the atmosphere; and means responsive to variations of pressure in the suction passage for actuating the valve.

6. In a carbureter, the combination of a 105 suction passage; an intermediate chamber having communication with a fuel supply, with said suction passage and with the atmosphere; a secondary chamber communicating with the intermediate chamber; a 110 well in which fuel accumulates; a passage leading from the lower part of the well to said secondary chamber; a passage leading from the well to the atmosphere; a valve controlling the communication between said 115 secondary chamber and the atmosphere; and means responsive to variations in pressure in the suction passage controlling said valve.

7. In a carbureter, the combination of a 120 suction passage; a well in which fuel accumulates and having an opening to the atmosphere; a connection leading from below the fuel level in the well to the suction passage; an air passage leading from the connection to the atmosphere; a valve controlling said air passage; and means responsive to variations of pressure in the suction passage controlling the valve.

8. In a carbureter, the combination of a 125 suction passage; a well in which fuel ac-

1
cumulates and having an opening to the atmosphere; a connection leading from below the fuel level in the well to the suction passage; an air passage leading from the connection to the atmosphere; a valve controlling said air passage; means responsive to variations of pressure in the suction pas-

sage controlling the valve; and means controlled by said valve effecting a continued supplemental delivery of fuel to the suction 10 passage following a closing of said valve.

In testimony whereof I have hereunto set my hand.

FRANK H. BALL.
